UNITED STATES PATENT OFFICE

2,434,881

ABRASIVE CLEANING SYSTEM

Gilbert D. Dill, South Bend, Ind., assignor to
 American Wheelabrator & Equipment Corporation,
 a corporation of Delaware

Application December 29, 1945, Serial No. 637,922

8 Claims. (Cl. 51—9)

1

The invention relates to sheet blasting or cleaning equipment and more particularly to apparatus for threading or starting the leading edge of a metal strip or sheet through the blasting apparatus.

In descaling or cleaning steel sheet or strip by blasting, the work is fed through a blasting room or cabinet where the blasting wheels direct their blasts onto the work as it moves through the machine. An object of the invention is to provide a threading device which will transport the leading edge of flat material through the machine without requiring external equipment; another object is to eliminate the use of a dummy sheet or strip for transporting the leading edge of flat material through such a machine; another object is to provide a threading device which will permit blasting the leading parts of the flat material while it is being threaded through the machine.

According to a preferred form of the present invention, a carriage or platform is provided which is adapted to be power driven, either positively or frictionally, from the entrance of the cleaning room to its exit. This platform has a clamping device for clamping the leading edge of the work strip. This carriage pulls the work strip through the machine until the carriage reaches the exit end of the machine at which point the clamp is automatically opened and the work strip is continued through the machine by engagement with the several power driven rolls within the machine. Suitable vestibules are provided at the entrance and exit having access doors for operating the clamp. These vestibules also have suitable rubber curtains for sealing the entrance and exit points against the moving work sheet. The blasting units may be of the motor driven centrifugal wheel type known commercially as Wheelabraters which throw metal shot or grit at blasting speed against the surface of the work. One or more of the blasting machines may be located both above and below the work strip, and suitable provision is made for removing the blasting units from the machine for inspection or replacement with a spare.

The invention also consists in certain new and original features and combinations hereinafter set forth and claimed.

Although the novel features which are believed to be characteristic of this invention will be particularly pointed out in the claims appended hereto, the invention itself, as to its objects and advantages, and the manner in which it may be carried out, may be better understood by refer-

2

ring to the following description taken in connection with the accompanying drawings forming a part hereof, in which:

Fig. 1 is a side elevation of a complete machine utilizing a positive drive for the carriage;

Fig. 2 is an enlarged detail section taken parallel to Fig. 1;

Fig. 3 is a transverse vertical section taken on the line 3—3 of Fig. 2;

Fig. 4 is a transverse section, corresponding to Fig. 3, but taken through a modified form of machine having a frictional drive for the carriage;

Fig. 5 is a skeleton side elevation illustrating the frictional drive path through the friction drive type machine;

Fig. 6 is a skeleton plan view of the frictional drive type illustrating the path of the carriage through the machine;

Fig. 7 is a side elevation of the carriage including work clamp for the frictional drive type;

Fig. 8 is a plan view of the carriage shown in Fig. 7; and

Fig. 9 is a detail illustrating the construction of one of the supporting rolls.

In the following description and in the claims, various details will be identified by specific names for convenience, but they are intended to be as generic in their application as the art will permit.

Like reference characters denote like parts in the several figures of the drawings.

In the drawings accompanying and forming part of this specification, certain specific disclosure of the invention is made for purposes of explanation, but it will be understood that the details may be modified in various respects without departure from the broad aspect of the invention.

Referring now to the drawings and more particularly to the positive drive type of carriage as illustrated in Figs. 1 to 3, the apparatus comprises in general the usual framework 10 which supports the abrasive, circulatory apparatus which cleans the abrasive and feeds it back to the blasting wheels.

A cabinet indicated generally by 11 has longitudinal vertical side walls 12 and 13, a roof 14, entrance vestibule 15 and exit vestibule 16. Two removable up-blast units 17 and 18 clean the lower surface of the work strip 21 which is fed horizontally through the machine in the direction of arrow B. Two down-blast units 19 and 20 are located above the cabinet 11 and project partially through the roof 14 for cleaning the upper surface of the work strip 21.

The carriage 22 for threading the work through the machine is propelled by a plurality of power driven intermediate rolls 23. A pair of idler rolls 24 at the entrance end of the cabinet and a pair of idler rolls 25 and 25a at the exit end provide stationary entrance and exit positions for the carriage as explained more in detail below. Roll 25a is outside the cabinet.

The cabinet 11 comprises the blasting room 26 with which the entrance and exit vestibules 15, 16 communicate. The blasting room 26 is lined with a series of clapboard liner plates denoted in general by 35 which line the ceiling, side walls and end walls to absorb the wear of the abrasive which is deflected from the work. The cabinet is of knockdown welded construction for ease of handling in shipping and erection. The lining 35 comprises one inch thick steel overlapping wearing plates, weighing about eighty pounds each. These plates are hung on the frame by hooks denoted in general by 46 in such manner that they may be easily and quickly removed and replaced when worn.

The entrance vestibule 15 is provided with an entrance door 27 which may be opened to enable the attendant to manually place the leading edge of the work sheet or strip 21 into the clamp of carriage 22, as will be explained hereinafter. The exit vestibule 16 has a similar door 28. The vestibules are equipped with rubber curtains 29 and 30 around entrance and exit slots respectively to prevent abrasive leakage. End walls 87 and 88 protect the vestibules and have openings for passing the carriage and work strip. End wall 88 protects carriage 22 from abrasive when it rests on exit idlers 25 and 25a.

The cabinet is equipped with service doors to permit a workman to enter the room for necessary adjustments, inspection and repairs. Service door 31 is in wall 12 near the entrance end and is shown in Figs. 1 and 2. A similar service door is near the exit end in the opposite side wall 13. The room is provided with a steel grating floor 33 contained in a hopper 34 which collects the spent abrasive. Opposite door 31, on the other longitudinal side wall 13 is an opening 55 to remove up-blast unit 18 while, opposite the other service door in side wall 12, is another opening 55 to remove up-blast unit 17 (see Figs. 1, 2 and 3).

As stated above, the path of travel of the work through the machine includes the series of rubber covered rolls 23, 24, 25, 25a. All rolls are mounted on shafts indicated in general by 47 which project through the side walls of the cabinet and are journaled in suitable bearings 42 attached to the side walls. Suitable gears indicated in general by 43 are mounted on those shafts 47 which are power driven, idler gears 45 being provided for transmitting motion between the several shafts. These gears are all driven by a suitable reversible prime mover (not shown).

The rubber covered rolls 23, 24, 25, 25a may be of similar construction so only roll 23 will be described in detail. In one preferred form, (Fig. 9) the roll 23 is made up of a hollow metal pipe 47 having discs 48 welded in the ends thereof, which discs in turn have hubs 49 welded thereto. These hubs are mounted on the shafts 44 and fixed thereto by set screws or pins 50. These shafts extend a considerable distance beyond the ends of the rolls and have journals mounted in the bearings 42.

The outer surface of the pipe 47 is rough-cut spirally about one-sixteenth of an inch deep.

The cut starts from the middle and works outwardly, forming spirals 52 and 53 of opposite hand, toward each end of the roll, as indicated. The rubber coating 54 is suitably bonded or otherwise fixed to the steel surface of the roll. The spiral grooves 52 and 53 assist in bonding the rubber to the roll. The direction of the spiral will be in such relationship to the direction of forward rotation of the roll so as to cause any creepage of the rubber on the roll to move the rubber toward the middle of the roll.

Riding on the rubber covered rolls is the carriage 22 comprising in general a top plate 36 having an eccentric clamping device 37 operated by levers 38, one at each end of the clamp. The top plate 36 has depending side rails 39 whose lower surfaces may be in the form of racks 40 which engage rubber covered pinions 41 located on the power driven shafts 44 but not on the shafts of idler rolls 24, 25, 25a. Levers 38 engage a stop-bar 69 near the exit end to open the clamp as explained hereinafter. Details of construction of the carriage 22 and clamping device 37 may be similar to those of the carriage illustrated in Figs. 7 and 8 used in the friction driven form described hereinafter.

As stated, the up-blast units 17 and 18 are removable through openings 55 in the opposite longitudinal side walls of the cabinet, said openings being opposite their respective service doors. Each unit may be easily replaced by a spare unit in case of breakdown. The units are self-contained and are enclosed and protected from flying abrasive. Since they are substantially identical in construction, a description of one will suffice for both.

Each up-blast unit comprises a suitable frame or car 78 having flanged wheels 79 riding on tracks 80. The unit is withdrawn by rolling it, 40 motorside first, laterally through the side wall opening 55 onto portable extension tracks 94. For example, unit 18 is removable in the direction of arrow C, and unit 17 is removable in the direction of arrow D. The up-blast units are removably bolted in place by the flange on the car engaging the cabinet around the opening 55. Each unit has a drive motor 74 and a blast wheel 75, the blast wheel being mounted upon a shaft journaled in bearings 76. A V-belt drive 77 connects motor and blast wheel shafts.

The blast wheel 75 is disposed between protecting walls 81, 82 which form, with sloping end walls 92, 93, a wheel compartment. These walls are mounted upon the carriage or frame 78. The 55 wheel compartment is open at the bottom to avoid collecting abrasive and is open at the top to pass the upward directive blast against the work. The blasts are indicated by fan-shaped dot-and-dash lines in Fig. 3.

60 The wheel compartment walls cooperate with stationary plates or walls 90, 91 mounted in the cabinet. A shroud 83 covers the top and inner side of the carriage including bearings 76, motor 74 and belt 77 and meets with the wheel confining wall 81. Shroud 83 also meets with an open panel 96 which is secured to the carriage and which seats against the adjoining longitudinal side wall. Thus the motor 74 is open to the outside of the cabinet through opening 97 in panel 70 96 but the shroud and wheel confining walls prevent escape of abrasive through this opening.

Also mounted on the carriage 78 is a feed funnel 84 which directs abrasive into the center of the wheel from feed pipe 57, as will be understood by those skilled in the art.

The relationship of the several blast wheels 17-20 to the path of travel of the work through the machine is the same as illustrated in Fig. 6 illustrating the friction drive type where same reference characters indicate similar parts. The axes of the up-blast wheels 17, 18 are parallel to the direction of work travel. The wheels are not in line and the points of blast delivery are oppositely disposed. Each wheel forms a blast pattern on the work extending entirely across the width of the work.

The down-blast units 19, 20 are constructed and arranged similarly to the up-blast units except that no removing tracks are provided. These units are disposed outside of the cabinet 11 and are removable as by an overhead crane. The down-blast units have their points of delivery of abrasive from the wheels diametrically opposed as in the case with the up-blast wheels and each down-blast wheel forms a blast pattern on the work extending entirely across the width of the work.

It will be understood that the abrasive is fed to the blast wheels and is circulated in accordance with standard practice. Tracing briefly the circulatory path, the spent abrasive is received in the bottom hopper 34 which leads to the bottom of an endless bucket belt elevator which discharges into a separator for separating dust and dirt and thence into a storage hopper 32. From the storage hopper the abrasive is fed through suitable control devices to pipes 57 leading to the several blast units 17-20.

To use the apparatus, let it be assumed that the carriage 22 is at the entrance end of the machine on the entrance idler rolls 24. The operator opens the entrance door 27 and inserts the forward end of the work strip 21 into the eccentric clamp 37 and pushes levers 38 forward to clamp the work strip firmly onto the carriage 22.

The carriage may then be either pushed by hand or by existing feeding rolls (not shown) until the carriage racks 40 engage the first power driven roll pinions 41. Such existing feed rolls may be those which convey the work strip from storage rolls or from prior fabricating operations.

After the carriage 22 engages the first feed roll 23, the operator may then close the entrance door 27 and start the blast wheels to deliver abrasive. The positive engagement between the rubber covered pinions 41 and the carriage racks 40 assisted by frictional engagement between the carriage platform and the rubber covered driven rolls themselves, starts the carriage moving through the machine, the carriage engaging further driven rolls and pinions in succession. It will, of course, be understood that the several driven pinions 41 have proper angular positions on their shafts so that the teeth of the racks 40 will always mesh properly succeeding power driven pinions.

The power driven rolls and pinions then pull the carriage with its appended work strip through the machine without any further attention on the part of the operator. The carriage advances until the clamp levers 38 engage the work stop 69 which opens the clamp 37, immediately afterwards, the carriage overruns the last power driven roll and rests upon the two exit idlers 25, 25a with the carriage projecting out through the exit rubber curtains 30. The engagement between clamp levers 38 and stop 69 limits the travel of the carriage.

When the eccentric clamp 37 opens, the work strip 21 continues to move, being driven by the rubber covered power driven rolls 23 which directly engage it as it travels behind the carriage. 5 The work strip 21 continues to pass through the machine over the carriage platform, which is now stationary, and through the exit curtains 30 onto further rolls (not shown), if desired. Such further rolls may pull the work strip and deliver it to storage rolls or to further processing apparatus, depending upon the particular plant.

After the work strip 21 is completely fed through the machine and comes to an end, the carriage 22 may be returned to the entrance end by simply reversing the power driven rolls 23. 15 The operator must first open the exit door 28 and manually push the carriage 22 until it engages the nearest driven roll 23. The power driven rolls 23 then drive the carriage back to the entrance end onto the two entrance idlers 24 into position for starting a succeeding work strip. The blast may be turned off during the return travel of the carriage.

Referring now to Figs. 4 to 7, the friction type 25 is constructed generally similar to the positive drive type described above, and for simplicity, such similar parts in the friction type will be denoted by the same reference characters as used in the positive drive type. The main differences 30 in the friction type as compared with the positive drive type reside in the drive between carriage and rolls and in the manner of driving the roll shafts.

Thus, in the friction type, the drive pinions and 35 racks on carriage 22 are omitted and plain side rails indicated by 63 are used, which side rails cooperate with the ends of the rolls 23, 24, 25, 25a to guide the carriage in a straight path through the machine. Sprockets, indicated in general by 85, are mounted on the roll shafts 44 for driving the power driven rolls 23. Sprockets 85 are connected by chains, indicated in general by 86. As in the positive drive form, the entrance rolls 24 are idlers and the exit rolls 25 and 25a are 45 idlers. The sprocket and chain drive 85, 86 is driven in any desired manner from a source of reversible power, one of the roll shafts 44 being shown extended for the mounting of suitable drive mechanism. It will be understood that belts and pulleys may be substituted for the 50 sprockets and chains.

Referring now also to Figs. 7 and 8, the carriage 22 comprises a base plate or platform 60 which comprises a top plate 61 with depending side bars 62 and 63 secured thereto on its lower 55 surface.

An eccentric clamp 37 is provided at the rear end of the carrier. The upper surface of the carrier has a bearing bracket 65 at each end journaling a shaft 66 having an eccentric knurled surface roll 67 thereon extending substantially entirely across the carrier. The shaft 66 is journaled in the brackets 65 and carries an operating arm 38 at either end. The front edge of the work strip 21 is adapted to be clamped between the eccentric roll 67 and the top base plate 61 by moving the operating arm in the direction of the arrow A in Fig. 7. It will be understood that, when the carrier moves through the machine, the operating arms 38 engage the cross bar 69 as discussed above, which automatically loosens the clamp to permit free movement of the work strip 21 through the clamp 37.

Suitable stops 70 are provided to limit the 75 movement of the clamp and thus the pressure ex-

erted on the work strip. It will be noted that the depending guide bars 62, 63 are beveled at front and rear, as indicated at 71, 72, to facilitate engagement with the rolls. Also, the base plate 61 is beveled at its rear end at 74 to facilitate threading the work strip into the clamp.

It will be noted that the upper surface of the platform top plate 61 is above the surface of the rolls 23, 24. This difference in height, which may be about one inch, raises the leading edge of the work strip or sheet and creates a drag on the cam wedge eccentric roll clamp and maintains the locking action.

The friction type is useful where only light traction is necessary to drag the work through the machine. The positive drive type is useful, particularly where heavy traction is required to drag the work through the machine. In either case, the carriage is returned by reversing the direction of the rolls.

In this device only a few inches of the work is wasted by not being cleaned, otherwise the material required to thread the machine before starting the blast wheels would be wasted. Such wasted length in some cases may be as much as thirty feet.

Thus a threading or starting device is provided which starts a new sheet or strip through a cleaning machine without requiring any outside feeding devices, all parts of the threading device being provided within the machine itself. With the present invention, only the very small forward margin of the strip engaging the clamp is uncleansed. The blasting operation may be started as soon as the leading edge of the work is placed in the clamp and the carriage is engaged with the power driven rolls since the carriage is dragged or propelled through the machine entirely by power. After the work is started through the machine, the feeding device is automatically disconnected so that the work continues to pass through the machine uninterruptedly. When the work is completed and it is desired to feed a new work sheet through the machine, the threading device is easily returned from the exit end to the starting end of the machine. All parts subjected to abrasive blast are rubber covered for protection.

While certain novel features of the invention have been disclosed herein, and are pointed out in the annexed claims, it will be understood that various omissions, substitutions and changes may be made by those skilled in the art without departing from the spirit of the invention.

What is claimed is:

1. In a device for starting a strip or other sheet through a cleaning machine, a cabinet having an entrance and an exit, a plurality of rolls forming a path for the strip, certain of said rolls at the entrance and at the exit being idlers, the intermediate rolls being power driven, a carriage cooperating with said rolls and having a holding device for holding said strip, stop means cooperating with said holding device for releasing said strip when the carriage reaches its exit position, said strip thereafter passing freely through the carriage and being propelled by said power driven rolls, said power driven rolls being reversible to return the carriage to its entrance position.

2. In a threading device for starting a strip or other sheet through a cleaning machine, a cabinet having an entrance wall and an exit wall, said walls having slots for passing the work strip, a plurality of horizontally extending rolls in said cabinet, certain of said rolls at said entrance

and certain of said rolls at said exit being idlers, the intermediate rolls being power driven, means for journaling said rolls, a carriage comprising a top plate with depending side rails adapted to ride respectively on the top and at the ends of said rolls, a clamping device on said carriage, said cabinet having a stop device operable, when said carriage approaches its exit position, to open said clamping device, said strip thereafter passing freely through said clamping device being propelled by said power driven rolls, said power driven rolls being reversible to return the carriage to its entrance position.

3. In a device for starting a strip or other sheet through a blasting machine, a cabinet having an entrance and an exit, a path for the strip connecting said entrance and exit, a carriage traversing said path, said carriage having a holding device for holding said strip, means propelling said carriage along said path, stop means cooperating with said holding device for releasing said strip when the carriage reaches a predetermined position, means for thereafter propelling said strip freely through the carriage.

4. In a threading device for starting a strip or other sheet through a treating machine, a cabinet having an entrance and an exit, a plurality of horizontally extending rolls in said cabinet, certain of said rolls at said entrance and certain of said rolls at said exit being idlers, the intermediate rolls being power driven, means for journaling said rolls, a carriage comprising a top plate with depending side rails adapted to ride respectively on the top and ends of said rolls, a clamping device on said carriage, said cabinet having a stop device operable, when said carriage approaches its exit position, to open said clamping device, said strip thereafter passing freely through said clamping device being propelled by said power driven rolls.

5. In a threading device for starting a strip or other sheet through a cleaning machine, a cabinet having an entrance vestibule and an exit vestibule, said vestibules having in their end walls service doors and slots for passing the work strip, a plurality of transverse horizontally extending rolls in said cabinet, certain of said rolls at said entrance and certain of said rolls at said exit being idlers, the intermediate rolls being power driven rolls, pinions attached to the intermediate rolls, means for journaling said rolls, drive gears on said power driven rolls outside said cabinet, a carriage comprising a top plate with depending side rails adapted to ride respectively on the top and at the ends of said rolls, said carriage having stationary entrance and exit positions on corresponding idler rolls, said rails having racks engageable with said pinions, a clamping device at the rear end of said carriage, said clamping device comprising a pivoted cam, a lever attached to said cam, said cabinet having a stop device near the exit vestibule engaged by said lever when said carriage approaches its exit position to open said clamping device, said strip thereafter passing freely through said clamping device and being propelled by said power driven rolls, said power driven rolls being reversible to return the carriage to its entrance position.

6. In a threading device for starting a strip or other sheet through a cleaning machine, a cabinet having an entrance wall and an exit wall, said walls having slots for passing the work strip, a plurality of horizontally extending rolls in said cabinet, certain of said rolls at said entrance

entrance and certain of said rolls at said exit being idlers, the intermediate rolls being power driven rolls, pinions attached to the intermediate rolls, means for journaling said rolls, a carriage comprising a top plate with depending side rails adapted to ride respectively on the top and at the ends of said rolls, said carriage having stationary entrance and exit positions on corresponding idler rolls, said rails having racks engageable with said pinions, a clamping device at the rear end of said carriage, said clamping device comprising a pivoted cam, a lever attached to said cam, said cabinet having a stop device engaged by said lever when said carriage approaches its exit position to open said clamping device, said strip thereafter passing freely through said clamping device being propelled by said power driven rolls, said power driven rolls being reversible to return the carriage to its entrance position.

7. In a threading device for starting a strip or other sheet through a cleaning machine, a cabinet having an entrance wall and an exit wall, said walls having slots for passing the work strip, a plurality of horizontally extending rolls in said cabinet, certain of said rolls at said entrance and certain of said rolls at said exit being idlers, the intermediate rolls being power driven, means for journaling said rolls, a carriage comprising a top plate with depending side rails adapted to ride respectively on the top and at the ends of said rolls, said carriage having stationary entrance and exit positions on corresponding idler rolls, said carriage having frictional engagement with said rolls, a clamping device at the rear end of said carriage, said clamping de-

vice comprising a pivoted cam, a lever attached to said cam, said cabinet having a stop device engaged by said lever when said carriage approaches its exit position to open said clamping device, said strip thereafter passing freely through said clamping device being propelled by said power driven rolls, said power driven rolls being reversible to return the carriage to its entrance position.

- 10 5 8. In a blasting machine for blasting strip and the like, said machine having an entrance zone, an exit zone and a blasting zone extending therebetween, blasting devices for treating the strip passing through said blasting zone, a carriage traversing said blasting zone between entrance and exit zones, said carriage having a holding device for holding the forward part of said strip, means for propelling the carriage to pull the strip through the machine, stop means 15 cooperating with the holding device for releasing the holding device when the carriage reaches said exit zone, and means for thereafter propelling the strip through the carriage and through the machine.
